UNITED STATES PATENT OFFICE.

JOSEPH J. ATKINSON, OF HOUSTON, TEXAS.

BALING-PRESS.

SPECIFICATION forming part of Letters Patent No. 698,353, dated April 22, 1902.

Application filed April 17, 1901. Serial No. 56,253. (No model.)

To all whom it may concern:

Be it known that I, JOSEPH J. ATKINSON, a citizen of the United States, residing at Houston, in the county of Harris and State of Texas, 5 have invented a new and useful Baling-Press, of which the following is a specification.

This invention relates to baling-presses of the roller type which are designed for making round or cylindrical bales of cotton and 10 similar material and comprising means for forming the bale from highly-compressed layers laid spirally endwise of the bale, or rather of the column of fiber, which when completed constitutes the bale. A baling- 15 press of this character is described and illustrated in my concurrent application for Letters Patent, Serial No. 25,938, filed on or about August 4, 1900, and my present invention is intended as an improvement of the press 20 therein shown. In the application aforesaid the press comprehends a compressing device or head employed to draw in the cotton or other material from a supply in bulk and to compress the same into condensed flattened 25 layers laid endwise of the column of fiber by the relative rotation of the compressing device and the baling cylinder or chamber usually in subjacent relation to the compressing device. Suitably journaled in the compress- 30 ing-head and bodily movable with the latter are a number of conical compressing-rollers arranged in a circular series or horizontally-arranged group, and the invention, so far as the companion application was concerned, re- 35 sisted in the positive rotation of these rollers at a higher rate of speed than can possibly be obtained from the surface friction of the rollers and also in the provision of means for varying the peripheral speed of the rollers by 40 shifting them longitudinally to increase their diameters within the vertical plane of the baling cylinder or chamber. The additional peripheral speed of the compression-rollers obtained by their positive actuation contrib- 45 utes materially to the successful operation of the press, because the inner or smaller ends of the conical rollers are thus made to revolve about fifteen per cent. faster than they would revolve if impelled simply by frictional 50 contact with a plain surface, while the outer ends of the rollers revolve at a speed about

ten per cent. faster than they would if frictionally driven in the manner stated—that is to say, the percentage of increased speed near the center of the bale is very much 55 greater than at the outside, and I have found that this peculiarity of my press is of great value and is attended with distinctly beneficial results, inasmuch as the additional peripheral speed imparted to the rollers permits 60 them to overcome the swell or undulation produced in the cotton between the rollers, and thus overcome the tendency of the cotton to bank up between the rollers or to pass above them through the intermediate 65 spaces.

During the course of a series of experiments with the press as described in the application above identified I have found that the cotton as it is laid between the rollers has a 70 tendency to draw toward the center of the bale. This is apparently due to the rotary movement imparted to the cotton at the top of the bale by the rotation of the compressing-head and its rollers, and if permitted to continue 75 would result in the formation of a bale lacking that uniformity of density which is essential to the commercial value of bales of this character—that is to say, the movement of the cotton toward the center of the bale or 80 the inward drawing of the cotton serves to effect the undue compression of a comparatively large body of fiber at the center of the bale, the body of fiber at the outer edge of the bale being correspondingly decreased. 85 While this tendency of the press as originally constructed was not sufficient to render the press impractical or to offset the many advantages accruing from the novel features thereof, it is nevertheless desirable to provide 90 means for overcoming this tendency of the cotton at the top of the bale to move toward the center thereof, and the accomplishment of this end is the primary object of the invention now under consideration. 95

The primary object of the invention may therefore be said to be the prevention of the inward-drawing or centripetal movement of the fiber in a press of the roller type.

To the accomplishment of this end the invention consists in providing means disposed intermediate of the rollers and within the 100

plane of the baling-cylinder for opposing resistance to the inward movement of the fiber and overcoming to a greater or less extent the tendency of the upper layer of cotton to 5 form waves or billows in advance of the rollers; and the invention consists, still further, in the construction and arrangement of parts to be hereinafter fully described, illustrated in the accompanying drawings, and embraced 10 within the scope of the appended claims.

In said drawings, Figure 1 is a side elevation of a baling-press embodying the improvements contemplated by the present invention. Fig. 2 is a top plan view of the subject- 15 matter of Fig. 1. Fig. 3 is a vertical transverse sectional view on the line 3-3 of Fig. 2. Fig. 4 is a detail sectional view on the line 4-4 of Fig. 2 looking in the direction indicated by the arrow on said figure, and Fig. 20 5 is a detail sectional view on the line 5-5 of Fig. 2 looking in the direction indicated.

The same numerals of reference will be employed to designate corresponding parts throughout the several views.

25 In the practice of the present invention the ordinary parts of the press may be constructed in any desired manner and mounted in any approved way to insure its proper operation; but for the purpose of illustrating the 30 novel features contemplated by the present invention I have shown an upright press-stand 1, resting upon a suitable base 2 and supporting at its upper end what I have termed a "top-supporting frame" 3, within 35 which are mounted the principal working parts of the press. In its present form the press comprises a pair of upright standards supporting a pair of upper and lower horizontal frame-plates 4 and 5, constituting the top- 40 supporting frame, and from the lower plate 5 depends the baling cylinder or chamber 6, differing from that shown in my concurrent application by being somewhat shorter, as I find that a baling-chamber of greater length 45 is unnecessary and merely adds to the expense of the press. The baling chamber or cylinder, which, as usual, conforms in contour and dimensions to the completed bale, accommodates the receding follower 7, associated with any suitable pressure mechanism, 50 which for illustrative purposes is shown in the drawings in the form of an ordinary hydraulic pressure mechanism 8, whose ram or piston 9 supports the receding follower 7 and 55 opposes such resistance to the recession of the follower as will effect the desired compression of the bale as the latter is formed in the manner described.

In that form of the invention illustrated in 60 the drawings the baling chamber or cylinder 6 is rigidly fitted to the lower frame-plate 5 in any suitable manner and registers with a central bale-opening 10, formed in said plate, which opening in turn is in registering relation with a central opening 10^a in the upper frame-plate 4, the latter opening being of

somewhat greater diameter than the opening 10 and designed to permit the passage of the loose cotton or other fiber to the baling mechanism. In the preferred construction of the 70 press the cylinder 6 is provided with a plurality of longitudinal tie-receiving slots 11, through which the bale-ties are passed to secure the bale in the usual manner before it is delivered from the press; but inasmuch as 75 I find the removable filling-strips recited in my former application to be unnecessary the slots 11 are left open in the present construction.

As in the former application, the present 80 invention resides particularly in the construction of the compressing-head 16, which is arranged within the top-supporting frame 3, immediately over the upper end of the baling cylinder or chamber 6, and disposed in a fixed 85 horizontal plane to constitute a rigid abutment resisting the endwise thrust of the compressed column of material within the baling cylinder or chamber, while also constituting means for feeding or drawing in the fiber 90 and compressing the same into condensed flattened layers laid spirally upon the end of the column by the relative rotation of the compressing-head and baling-chamber.

In the type of press shown it is of course 95 necessary to provide for the relative rotation of the compressing members—to wit, the compressing-head and the baling cylinder or chamber—although, generally speaking, it is unimportant which of these elements is caused to 100 rotate. In some forms of roller-presses the cylinder and the body of fiber or bale are rotated, while the compressing-head remains stationary, and, as in the present construction, it is equally possible and perhaps preferable 105 to accomplish the desired result by the employment of a fixed cylinder or chamber and a coöperating rotary compressing-head. The particular advantage in the latter construction over the former is that the rotation of 110 the head requires the application of less power than is necessary to rotate the baling-cylinder and the contained body of fiber or material being baled.

The compressing device or head 16 comprises a roller-carriage 17, preferably in the form of a hollow circular frame, formed with an outer pendent rim 18, the lower edge of which is disposed immediately outside of an upstanding bearing-flange 19, cast or otherwise formed upon the upper side of the lower frame-plate 5 and constituting means for retaining the roller-carriage in proper position for movement in a fixed circular plane. Any suitable means for operating the carriage 17 115 may be employed; but such means preferably comprehends the provision of a gear-wheel 20, formed at the upper corner of the carriage and meshing with a driving-pinion 21, keyed upon the inner end of a driving-shaft 22, journaled 120 in upstanding bearings 23, formed upon the frame-plate 4, the shaft 22 being driven by 125 130

the application of power from any suitable source. The roller-carriage 17 is provided with an open center disposed in the vertical plane of the baling-cylinder, and within this opening is arranged a series of radially-disposed conical compressing-rollers 24, having their inner and outer spindle extremities 25 and 26 disposed coaxially in an oblique plane to present the lower faces of the several rollers in the same horizontal plane, said rollers thereby constituting an abutment for the upper end of the column of compressed material within the chamber 6. The compressing-rollers 24 radiate from the center of the roller-carriage in spaced relation, and their inner spindle extremities 25 are loosely journaled in the inner bearings 27, provided in a bearing-hub 28, fixed at the center of the central opening through the roller-carriage 17 and rigidly retained—as, for instance, by a plurality of brace bars or webs 29, extending radially from the hub 28 to the inner circular wall 30 of the roller-carriage, which wall is arranged somewhat differently from the inner wall of the press as originally constructed and constitutes, in a manner which will be made plain, the means for opposing resistance to the centripetal movement of the cotton. The rollers 24 are capable of longitudinal movement and are provided, as in the previous construction, with adjustable bearings in the form of adjustable screws 31, engaging threaded openings 32 in the outer rim 18 of the carriage; but instead of pointing the inner ends of these screws for engagement with correspondingly-shaped sockets in the outer spindle extremities 26 of the rollers I now contemplate the introduction of an antifriction-ball 33 intermediate of the contiguous ends of each outer spindle and the adjacent screw, the provision of these antifriction devices serving to decrease the loss of power occasioned by the end thrust of the roller upon its bearing. For the purpose of positively operating the compression-rollers through the rotation of the movable press element or member each of said rollers is provided with a driving-gear 35, splined upon the outer spindle extremity 26 of the roller and having an annularly-grooved journal-hub 36, journaled in a bearing 37, formed in a pendent bearing-hanger 38, located within the roller-carriage and extending downwardly in an outwardly-inclined direction from the top wall thereof. This form of mounting leaves the rollers free to be adjusted longitudinally for the purpose of increasing the surface speed thereof with respect to the fiber being compressed and at the same time permits the several gears 35 to rotate the rollers by engagement with a circular rack 39, preferably formed in the upper surface of the frame-plate 5, so that as the compressing-head of the press is rotated it will constitute the medium through which rotary movement is imparted to the several rollers at a higher rate of speed than could possibly

be obtained from mere frictional contact of the rollers with a plain surface.

In my previous application I have described in detail the manner of effecting the adjustment of the rollers to increase their diameters within the vertical plane of the baling cylinder or chamber in order to increase the peripheral speed of the rollers, and while I do not consider it necessary to enter into an exhaustive discussion of this phase of the press, at the same time it may be stated that in forming a bale beneath conical compressing-rollers the upper end of the compressed column of material lying immediately under the rollers is not flat throughout, but presents a wavy undulating surface defining crests or ridges in the spaces between the rollers. The positive rotation of the rollers serves to cause them to surmount these crests or ridges and prevents the material from accumulating in advance of the rollers and blocking the operation of the device. I have found, however, that while the original construction is highly effective and practical and is a decided advance in the art, still it has been observed that in the operation of the press there is a tendency of the cotton to draw inwardly from the outer edge of the bale toward the center thereof—that is to say, more or less rotary movement is given to the upper surface of the bale by the rotation of the roller-head, and this movement, combined with the variation of surface speed at different points in the length of the roller, serves to effect more or less centripetal movement of the fiber, which while not amounting to a vital objection is none the less undesirable, and its elimination has called for the exercise of inventive genius, resulting in the origination of the subject-matter of this application. Obviously the most effective manner of overcoming this indrawing or centripetal movement of the fiber passing under the rollers is to oppose the necessary resistance to the fibrous mass adjacent to that point from which the fiber has a tendency to draw. In carrying out the present invention, therefore, I utilize the inner circular wall 30 of the roller-carriage 17, and in order to adapt this wall for the performance of the function stated I provide a simple construction which serves to locate the wall entirely within the vertical plane of the bale, so that the upper end of the latter is forced upwardly against the lower edge of the wall 30 adjacent to the outer edge of the bale. The inner wall 30, which by reason of its new function I shall term a "compression-ring," is, therefore, of less diameter than the diameter of the chamber or cylinder 6 and is recessed for the passage of the rollers 24, the lower edges of which are disposed in a slightly-lower plane than the lower edge 39^a of the compression-ring or wall 30, the edge 39^a being preferably rounded, as shown, to prevent injury of the fiber. The ring 30 is supported at its upper end by a spacing-ring 40, interposed between the ring

30 and a guard-ring 41, secured within the opening 10 in the top wall of the roller-carriage, the rings 40 and 41 being located in the plane of the top wall of the carriage instead 5 of being pendent therefrom.

In the present embodiment of the invention I have illustrated a single feeding-space 42, defined between a pair of rollers separated to a slightly-greater extent than the others, and 10 in order that the feeding-space may extend from the hub 28 to the extreme interior surface of the cylinder 6 the compression-ring 30 is cut away at one side to form a vertical feed-slot 43, (see Fig. 5,) the front wall 44 of 15 which is inclined and the rear wall 45 of which is vertically disposed and is located substantially in the vertical plane of the axis of one of the rollers 24. It is evident, however, that this opening must be guarded to 20 confine the cotton to the vertical plane of the cylinder—that is to say, a guard must be provided to prevent the fiber escaping through the slot 43 from extending laterally beyond the vertical plane of the cylinder-walls. I 25 therefore form a pendent guard-plate 46 upon the guard-ring 41, said guard-plate being disposed opposite the slot 43 and of sufficiently greater width than said slot to prevent the escape of the fiber, (see Figs. 3 and 4,) attention being called to the fact that this guard-plate 46 extends practically to the upper face of the bottom plate 5.

While the machine is in operation, the press-rollers 24 revolve a fraction more during each 30 rotation of the roller-carriage than they would if their revolution was effected simply by frictional contact with a plain surface, and while the provision for varying the peripheral speed of the rollers serves to overcome 35 in large measure the banking of the material in advance of the rollers the objectionable inward-drawing or centripetal movement of the fibers is produced, as heretofore stated. It is impossible, however, to entirely overcome 40 the tendency of the upper surface of the bale to undulate, and as a consequence more or less of the fiber will extend upwardly between the rollers as the bale is being formed. In accomplishing the object of the 45 present invention I take advantage of this fact, and by disposing the circular wall or compression-ring 30 within the circumferential plane of the bale I oppose an effective resistance to the upper surface of the bale at a 50 point adjacent to the outer edge thereof and at the same time remove the compression device or ring to a sufficient distance above the lower edges of the rollers to prevent any interference with the proper compression of the 55 bale or with the feeding of the fiber to the press. In other words, I find that the inward drawing of the fibers toward the center of the bale may be counteracted by holding down the 60 extreme outer edges of the bale by a pressure which will be just sufficient to prevent the 65 cotton from slipping inward from underneath

the compression device, but which will not be sufficient to injure the fiber as the compressing member is moved with the compressing-head, and the result is that a bale of uniform density is produced and all liability of 70 clogging the machine is obviated. The general operation of the press is well understood by those skilled in the art and need not, therefore, be detailed for the purpose of this 75 exposition.

From the foregoing it will be observed that I have produced a baling-press of the roller type embodying means for preventing centripetal movement or the indrawing of the 80 fiber from the edge of the bale toward the center thereof; but while the present embodiment of the invention appears at this time to be preferable I desire to be distinctly understood as reserving to myself the right to effect such changes, modifications, and variations of the illustrated structure as may be suggested by experience and experiment so long as they are properly embraced within the scope of the protection prayed. 90

What I claim is—

1. In a press of the character described, the combination with a baling-chamber and a compressing-head, of means for effecting the relative rotation of the head and chamber, and 95 means for opposing resistance to the undue drawing of the fiber, of the bale located within the chamber, toward the center of the bale from the outer portion thereof.

2. In a press of the character described, the combination with a baling-chamber and a compressing-head, of means for effecting the relative rotation of the head and chamber, and a compression member carried by the head and bearing against the face of the bale at or adjacent to the outer edge only thereof to prevent the undue drawing of the fiber toward the center of the bale. 105

3. In a press of the character described, the combination with a follower and a compressing-head including a series of compressing members, of a compression device disposed intermediate of the compressing members and bearing against the face of the bale to prevent undue drawing of the fiber toward the 115 center thereof.

4. In a press of the character described, the combination with a baling-chamber, of a compressing-head arranged over said chamber, a circular series of conical rollers supported by 120 said head and disposed within the plane of the baling-chamber, means for causing a relative rotation between the baling-chamber and said compressing-head, and means disposed intermediate of the rollers for opposing resistance to the undue drawing of the fiber toward the 125 center of the bale.

5. In a press of the character described, the combination with a baling-chamber, of a compressing-head arranged over said chamber, a circular series of conical rollers supported by 130 said head, means for causing a relative rota-

tion between the baling-chamber and said compressing-head, and a compression-ring disposed to bear against the end of the bale at points intermediate of the rollers to oppose a resistance to the undue drawing of the fiber toward the center of the bale.

6. In a press of the character described, the combination with a baling-chamber, of a compressing-head arranged over said chamber, and provided with a compression-ring located above, but within the circumferential plane of, said chamber, a circular series of conical rollers supported by said head and disposed in the vertical plane of the baling-chamber, the under sides of said rollers being disposed in a plane slightly below the plane of the lower edge of the compression-ring, and means for causing a relative rotation between the baling-chamber and said compressing-head, whereby the bale will be compressed and undue drawing of the fibers toward the center of the bale will be prevented by the compression-ring.

7. In a press of the character described, the combination with a baling-chamber, of a compressing-head arranged over said chamber and provided with a compression-ring, concentric with but of smaller diameter than the chamber and divided to form a feed-opening, a guard for said feed-opening disposed substantially in the vertical plane of the wall of the baling-chamber, and a series of conical rollers supported by said head and passed through the compression-ring.

35 8. In a press of the character described, the combination with a baling-chamber, of a compressing-head arranged over said chamber, and having a pendent inner wall constituting a compression-ring concentric with but of smaller diameter than the baling-chamber, and a series of compressing-rollers supported by the head and passed through the compression-ring.

9. In a press of the character described, the combination with a baling-chamber, of a compressing-head arranged over said chamber and provided with a pendent inner wall constituting a compression-ring concentric with but of smaller diameter than the baling-chamber, said wall being divided to form a feed-opening, one side of which is inclined, a guard-plate disposed directly opposite the feed-opening, and a circular series of conical rollers supported by the head and passed through the guard-ring, said rollers being disposed to define a feed-space in line with the opening in the ring.

10. In a press of the character described, the combination with a baling-chamber, of a compressing-head arranged over said chamber and having a pendent inner wall concentric with but of smaller diameter than the chamber, and divided at one side to form a feed-opening, a spacing-ring encircling the upper end of the compression-ring, a guard-ring encircling the spacing-ring and retained

within the head, said guard-ring being provided with a pendent guard-plate arranged opposite the opening in the ring, a series of conical rollers supported by the head, and means for effecting the relative rotation of the head and chamber.

11. In a press of the character described, the combination with a baling-chamber, of a compressing-head arranged over said chamber, a circular series of conical rollers supported by said head and disposed within the plane of the baling-chamber, means for causing a relative rotation between the baling-chamber and the compressing-head, means for positively actuating the rollers, and means disposed intermediate of the rollers for resisting the undue drawing of the fiber toward the center of the bale from the outer portion thereof.

12. In a press of the character described, the combination with a baling-chamber, of a compressing-head provided with a series of conical rollers supported by said head and having suitably-journalized inner and outer spindles, adjustment-screws disposed to shift said rollers longitudinally, and antifriction-balls interposed between the screws and the adjacent ends of the roller-spindles.

13. In a press of the character described, the combination with a follower, of a compressing-head arranged over said follower, a circular series of conical rollers supported by said head, means for causing a relative rotation between said follower and said compressing-head, and a compressing-ring disposed to bear against the end of the bale at points intermediate of the rollers to oppose a resistance to the undue drawing of the fiber toward the center of the bale.

14. In a press of the character described, the combination with a follower, of a compressing-head arranged over said follower and provided with a compression-ring concentric with but of smaller diameter than the follower and divided to form a feed-opening, and a series of conical rollers supported by said head and passed through the compression-ring.

15. In a press of the character described, the combination with a follower, of a compressing-head arranged over said follower and having a pendent inner wall constituting a compression-ring concentric with but of smaller diameter than the follower, and a series of compressing-rollers supported by the head and passed through the compression-ring.

16. In a press of the character described, the combination with a follower, of a compressing-head arranged over said follower, and composed of a series of conical rollers, said head having a pendent inner wall constituting a compression-ring concentric with but of smaller diameter than the follower, and means for imparting an independent positive rotation to said rollers at slightly more than normal speed.

17. In a press of the character described, the combination with a baling-chamber, and a compressing-head, of means for effecting the relative rotation of the head and chamber, 5 and means located within the chamber for opposing resistance to the undue drawing of the fiber toward the center of the bale from the outer portion thereof.

In testimony that I claim the foregoing as my own I have hereto affixed my signature in 10 the presence of two witnesses.

JOSEPH J. ATKINSON.
